WILHELM R. NAGEL AND FRIEDRICH L. NAGEL, OF PADUCAH, KENTUCKY, ASSIGNORS
TO W. R. NAGEL & COMPANY, OF PADUCAH, KENTUCKY, A PARTNERSHIP COM-
POSED OF WILHELM R. NAGEL AND FRIEDRICH L. NAGEL

PROCESS OF CURING TOBACCO

No Drawing.

Application filed October 16, 1930. Serial No. 489,227.

This invention relates to a new and beneficial tobacco product and process of treating tobacco to produce the same; and more particularly to a process of flavoring and curing leaf tobacco to diminish its ill effects on the human system and improve its flavor and desirability for human consumption.

An object of the present invention is to produce a superior grade of tobacco for use in smoking and which will have a delightfully cool, non-irritating and fragrant taste and smoke. This tobacco also possesses a healthful therapeutic value, as it contains sassafras, which is a recognized medicament and which, when drawn into the throat and lungs, has the disinfecting and purifying effects of sassafras root.

In carrying out the invention, the following process may be utilized:

Raw leaf tobacco, after the customary drying, is subjected to live steam to initially soften it, after which it is packed in layers into its ultimate container. Upon each layer is smeared or otherwise applied a fairly thick coating of a mixture prepared in the following manner:

To $3\frac{1}{2}$ gallons of fuller's earth filtered amber petroleum jelly is added 1 pint of glycerine, the petroleum jelly being heated to a degree just below its melting point, after which the glycerine is added thereto with thorough stirring. After the stirring operation, 1 pint of oil of sassafras is added to the mixture and the mass thoroughly agitated.

The mixture thus prepared is smeared on to the leaf tobacco as it is put in its ultimate container, layer by layer, in the proportion of approximately 1 part mixture to 4 parts leaf tobacco. After the container has thus been filled with alternate layers of tobacco and mixture, it is left for a period of 12 hours and then subjected, while in the container, to a pressure of approximately 4,000 pounds per square inch. This reduces the bulk to approximately 40% of its original volume.

After this pressing operation, which is conducted by any suitable means, such as a hydraulic press, the container is closed with its top and then placed in a hermetically sealed curing house, where it is allowed to cure under a uniform heat of approximately 250° F. for a period of 10 days. At the expiration of the curing, the tobacco is in a finished condition and is suitable for human consumption.

Tobacco thus prepared has a delectable flavor and aroma, and when smoked is mild and does not produce any ill effects on the stomach and heart, as does tobacco as commonly cured, and is healthful, as it contains the purifying and therapeutic characteristic of sassafras root. The process also imparts to the tobacco a velvety smoothness, and when burned gives off a very cool smoke which does not bite the tongue. These characteristics make the invention of special value.

The invention is not restricted to the details of the process as variations may be introduced without materially affecting the product.

What is claimed is as follows:

1. The process of flavoring tobacco which comprises impregnating said tobacco with oil of sassafras dissolved in petroleum jelly.

2. The process of treating leaf tobacco which comprises coating said tobacco in the leaf with a mixture of oil of sassafras dissolved in petroleum jelly and glycerine in the ratio, by weight, of 1 part oil of sassafras mixture to 4 parts leaf tobacco.

3. The process of curing and flavoring leaf tobacco by subjecting it to live steam to soften it, coating it with a mixture of petroleum jelly, glycerine, and oil of sassafras, packing the coated tobacco in layers in a container and subjecting it to pressure of the order of four thousand pounds per square inch to reduce it to about forty percent of its original volume, and subjecting the pressed tobacco in said container to uniform heat of approxi-

mately 250° F. for a period of about ten days, substantially as described.

4. A new tobacco product comprising steamed leaf tobacco impregnated with a mixture of oil of sassafras and petroleum jelly in proportions to give it pleasant and healthful characteristics.

In testimony whereof, we have signed our names to this specification.

10   WILHELM R. NAGEL.
                         FRIEDRICH L. NAGEL.
